UNITED STATES PATENT OFFICE.

CARL J. PEARSON AND SIGRID L. M. PEARSON, OF CHICAGO, ILLINOIS.

PHONOGRAPH.

1,419,514.

Specification of Letters Patent. Patented June 13, 1922.

Application filed September 11, 1919. Serial No. 323,189.

To all whom it may concern:

Be it known that we, CARL J. PEARSON, and SIGRID L. M. PEARSON, citizens of the United States, residing at Chicago, in the 5 county of Cook and State of Illinois, have invented certain new and useful Improvements in Phonographs, of which the following is a specification.

This invention relates to sound producing instruments, such as phonographs, graphophones, and the like, and particularly to those which are used for musical purposes; and it has for its object the improvement of the tones produced by the instrument. One of the methods by which the tone is improved provided by our invention is by the use of means for cleaning the groove of the record as the instrument is in use, and at the same time for lubricating 20 the groove in a suitable manner, so as to reduce to a minimum the roughness of the groove and the friction of the needle therein.

Another object of the invention is to provide a horn or trumpet on each side of the 25 sound box, so that the sound may not only be passed downwardly into the casing of the phonograph in an ordinary manner, but may also be passed directly out from the sound box. A further object of the invention is to 30 improve the horn by means of its shape, by suitable shutters, and otherwise, and particularly by the introduction in an improved manner of suitable framework supporting properly tuned strings or wires. Other objects of the invention will be apparent from 35 a consideration of the accompanying drawings and the following description thereof.

Of the drawings Fig. 1 is a vertical sectional view of a phonograph embodying the 40 features of our invention. Fig. 2 is a fragmental elevation of the front portion of the horn. Fig. 3 is a sectional view along the line 3—3 of Fig. 1. Fig. 4 is an elevation of a shutter used in connection with the 45 horn. And Fig. 5 is a plan view of an additional trumpet which we provide.

It is well understood that in the use of sounding instruments where a needle plays in the groove of a record, that dust, and 50 shavings from the record, and the like, cause more or less harshness of sound when the instrument is in use; and to eliminate this largely we provide a suitable brush 10 which is fixed to the sound box 11 in any suitable 55 manner, for example by means of the spring

12 connecting the box and brush. The brush is so arranged that it immediately precedes the needle 13, as the needle slides in the ordinary manner in the sound grooves of the record 14, which is rotating thereunder 60 on the ordinary table 15. The brush 10 thus removes all loose substances from the groove and leaves it in suitable condition for the needle. At the same time we apply to the brush a suitable liquid of a lubricating na- 65 ture which not only slightly lubricates the groove, but also assists in causing the loose particles to adhere to the brush, and thus be removed. Any suitable form of brush may be used for the purpose. And any suitable 70 liquid may be used; but we prefer for the purposes an ordinary bristle brush and ordinary sewing machine oil. By these means much of the harshness of the sound is eliminated, and the tone is thereby materially 75 purified by the elimination of undesirable sounds.

To further improve the tone of the instrument we provide a passageway 16 connected at its upper end with the ordinary tapering 80 arm or trumpet 17, and opening at its lower end through a series of shutters 18 into the horn 20; the shape of the passageway and horn being substantially as is indicated in the drawing. It is to be understood, how- 85 ever, that the exact shape of the passageway and horn, so far as our invention is concerned, is not to be limited to the shape shown by the drawing.

Within the horn 20 we provide a plurality 90 of harps comprising frames 21, which, in this instance, are harp shaped, and which are adapted to fit snugly in the horn, being slidably supported therein by means of guide pieces 22, so that the frames may be 95 readily removed and interchanged when desired. Mounted on the frames are suitable adjustable pins 23, upon which are strung, in a usual manner the sounding wires or strings 24, the pins being arranged in an 100 ordinary manner so that the tension of the strings may be varied as desired. And also fixed in a suitable manner, to the frames are stiffening bars 25, which prevent yielding of the frame as the strings are tightened. As 105 the sound waves pass through the horn across the strings the vibrations thereof set up corresponding vibrations in the strings, and the tone of the instrument is materially improved thereby due partly to the fact that 110

the irregularities in the vibrations of the air waves passing through the box are more or less eliminated by the effect on the waves of the vibrations of the strings themselves.

5 It is to be understood that the tension of the strings may be varied in order to produce any desired combination of effects, and that the frames themselves may also be interchanged for this purpose. Further, by 10 changing the tension of the strings they may be tuned to various keys, and this may be conveniently done when the frames are removed from the horn.

By the use of the shutters 18 between the 15 chamber 16 and the horn, the intensity as well as the quality of the sound may be varied, depending upon the slant and the amount of opening of the shutters and also upon the particular tune that is being played 20 and the arrangement of the sounding strings. These shutters are manipulated by means of a bar 26, which is connected to each of the shutters 18, the shutters being pivoted at their ends 27 to the partition 28; so that, as 25 the bar 26 is pulled outwardly or pushed inwardly from the position shown in Fig. 1, the shutters will be closed more or less and the sound waves will be directed forwardly or backwardly. The position of the shutters 30 before the sound passes to the horn 20 thus gives an opportunity for varying the quality as well as the quantity of the sounds; and when desired the shutters may be closed entirely. At the same time the ordinary front 35 shutter may be used if desired.

To further purify the sound, and to otherwise improve the quality thereof, we provide a trumpet 30, which is fixed to the front side of the sound box 11, so that the vibrations of 40 the diaphragm 31 of the sound box is produced between the two trumpets 17 and 30, and the vibrations of the air pass outwardly through the trumpet 30, substantially the same as those pass inwardly through the 45 trumpet 17. The vibrations passing outwardly from the trumpet 30 combined with the vibrations passing downwardly from the horn 20 and the effect of the combination is to materially improve the quality of 50 the sound. As the waves passing into the trumpet 30 do not come from within the sound box 11, the harshness produced by the box itself is eliminated.

By the use of the trumpet 30 in combination 55 with the horn and the strings described, the intensity of the sound is maintained by the trumpet, while the quality is improved by the special arrangement of the horn and harps, and the pitch may be varied by the 60 tension of the strings. And the quality of the sound is further improved by the use of the brush 10; so that we are able by our improvements to produce tones purified by the 65 elimination of harsh or inharmonious sounds, without loss in the intensity of the tones,

and at the same time to improve the quality of the sounds.

Although we have described with some particularity the various structures which we have provided for purifying the tone of 70 sounding instruments, it is to be understood that various modifications may be made by those skilled in the art without departing from the spirit of our invention as disclosed by the following claims.

75

We claim as our invention:

1. In a phonograph a horn, a plurality of frames removably mounted in said horn, and a series of strings strung upon each of said frames, in combination with a conduit 80 for conveying the sound waves from the sound box of the phonograph to said horn under said strings whereby the said waves travel transversely of said strings.

2. In a phonograph a horn, a plurality of frames removably mounted in said horn, and a series of strings strung upon each of said frames, in combination with a conduit for conveying the sound waves from the sound box of the phonograph to said horn, and for 85 directing the waves across said strings.

3. In a phonograph a horn, a plurality of frames removably mounted in said horn, and a series of strings strung upon each of said frames, in combination with a conduit for 90 conveying the sound waves from the sound box of the phonograph to said horn, said conduit having an opening into said horn on the lower side thereof.

4. In a phonograph a horn, a plurality of 100 frames mounted in said horn, and a series of strings strung upon each of said frames, in combination with a conduit for conveying the sound waves from the sound box of the phonograph to said horn, said conduit 105 having an opening into said horn on the lower side thereof, and said strings extending across said opening.

5. In a musical phonograph, a casing, a sound box mounted on said casing, an elongated horn mounted substantially horizontally in said casing beneath said sound box, a wall closing the small end of said horn, said horn having a materially elongated 110 opening on its lower side, and a conduit operatively connecting the sound box of said phonograph with said opening.

6. In a phonograph, a sound box, a horn, a frame mounted in said horn, a plurality of elongated elastic articles fixed to said frame 120 and extending substantially from one end to the other of said horn, and a conduit connecting said box with said horn and arranged to direct the sound waves transversely of said articles.

125 In testimony whereof we hereunto set our hands.

CARL J. PEARSON.
SIGRID L. M. PEARSON.
